UNITED STATES PATENT OFFICE.

WILLIAM W. JONES, OF ENSLEY, ALABAMA.

AUTOMATIC TRAIN-STOP.

1,116,291.

Specification of Letters Patent.

Patented Nov. 3, 1914.

Application filed October 7, 1913. Serial No. 793,929.

To all whom it may concern:

Be it known that I, WILLIAM W. JONES, a citizen of the United States, residing at Ensley, in the county of Jefferson and State 5 of Alabama, have invented new and useful Improvements in Automatic Train-Stops, of which the following is a specification.

This invention relates to improvements in automatic train stops and has particular 10 application to a device of this character whereby the propelling power of a car or train as the case may be will be automatically cut off and the brakes applied in the event of such car passing a set danger signal 15 and entering the danger zone.

In carrying out the present invention, it is my purpose to provide an automatic train stop which will be constructed in such manner that the propelling power of the rolling 20 stock will be cut off and the air brakes applied in the event of the car or train passing a set danger signal and entering the danger zone and whereby the engineer or motorman will be enabled to regain control 25 of the propelling power and the brake system succeeding the passing of the danger signal so that such motorman or engineer may reverse the rolling stock and so back out of the danger zone.

30 It is also my purpose to provide an automatic train stop which may be installed and maintained at a minimum expense and which will operate efficiently and effectively for its intended purpose.

35 With the above and other objects in view, the invention consists in the construction, combination and arrangement of parts hereinafter set forth in and falling within the scope of the claim.

40 In the accompanying drawing: Figure 1 is a fragmentary side elevation of a trackway and locomotive thereon equipped with an automatic train stop constructed in accordance with my present invention. Fig. 45 2 is a view in elevation, of a portion of the car carried mechanism, parts being shown in section.

Referring now to the accompanying drawing in detail, A indicates a trackway, 50 while B designates a car, in the present instance, in the form of a steam locomotive designed to operate over the lines of rails of the trackway.

The numeral 1 designates a track trip or 55 obstacle composed of an elongated block having the opposite ends equipped with

trunnions 2, 2 journaled in suitable alining bearings 3, 3 carried by the ties of the trackway upon the outer side of the lines of rails thereof. This trip or obstacle is arranged 60 longitudinally of the lines of rails of the trackway and capable of swinging movement to active and inactive positions and when active lies in a vertical plane and in a horizontal plane when inactive. In the 65 present instance, this trip is equipped with an operating arm 4 which is preferably connected through the medium of suitable link mechanism with an armature under the control of an electro magnet connected in 70 an electric circuit under the influence of the track relay of the block signal system. In practice, a number of trips 1 are disposed along the trackway and spaced appropriate 75 distances apart and when used in conjunction with the automatic or train controlled block signal system one trip is disposed in proximity to each block signal so as to have control over the entrance to the block. If desired, these trips or obstacles may be directly connected with the respective block 80 signals through the medium of mechanical connections so that when the signals go to danger the trips will be rendered active, while when the signals are thrown to clear, 85 the trips will be rendered inactive.

The car carried mechanism of my improved train stopping apparatus embodies a cylinder 5 in which is mounted for sliding movement a piston 6 having a piston 90 rod 7 extending outwardly of one end of the cylinder and connected with a substantially U-shaped yoke 8 having the opposite limbs thereof slotted longitudinally, the slot in one limb receiving the throttle lever, 95 while the slot in the other limb receives the handle of the engineer's brake valve, the yoke being provided with guides 9 slidably disposed within suitable guideways 10. Fixed upon the piston rod 7 is a collar 11 100 spaced an appropriate distance from the stuffing box in the end of the cylinder 5 through which the rod passes and encircling the rod between such collar and stuffing box is a coiled expansion spring having one end 105 abutting the stuffing box and the opposite end in contact with the collar 11, such spring acting to hold the piston rod at its limit of outward movement so that the engineer, under ordinary conditions, has complete control of the throttle valve and the 110 brake valve. Leading into one end of the

cylinder is a fluid supply pipe 13 and located in such pipe is a three-way valve 14 which, in one position, establishes communication between the source of fluid supply 5 and the cylinder by way of the pipe 13 and in another position establishes communication between the cylinder and the atmosphere. This valve 14 is equipped with a handle 15 to which is connected one end of a lever 16 fulcrumed between its ends as at 17 and having its opposite ends connected to the upper extremity of a vertical rod 18 mounted for sliding movement within suitable bearings and having the lower end equipped 15 with a roller 19 adapted to ride upon the blocks constituting the trips.

In the present instance, I have shown the car carried stopping mechanism as installed in a steam locomotive and in this case the 20 pipe 13 is connected up with the steam space of the boiler so that when the valve 14 is opened the steam will pass from the boiler through the pipe 13 and into the cylinder 5 so as to slide the piston 6 in said cylinder 25 against the action of the spring 12 thereby drawing the piston rod 7 into the cylinder so as to unlock and swing the throttle valve to closed position and operate the engineer's 30 brake valve to emergency position. On the other hand, when the valve 14 is operated to establish communication between the cylinder and the atmosphere, the steam in said cylinder is exhausted and the spring 12 reacts to move the piston and piston rod to 35 normal position thereby enabling the engineer to regain control of the train.

From the foregoing description taken in 40 connection with the accompanying drawing, the construction, mode of operation and manner of employing my invention will be

readily apparent. Should a signal be set at danger, it will be seen that the respective trip will be rendered active so that should a train pass the danger signal and the active trip the roller 19 on the lower end of the 15 vertical rod 18 will ride upon the blocks constituting the trips with the effect to slide the rod 18 upwardly whereby the lever 16 will be swung about its fulcrum 17 to actuate the valve 14 and thus establish communication between the boiler and the cylinder 5, whereby the propelling power of the car will be cut off and the brakes applied as previously described. After the lower end of the rod 18 leaves the active 55 trip, such rod gravitates to its lowered position whereby communication between the boiler and the cylinder 5 is cut off and the cylinder placed in open communication with the atmosphere so that the steam within the cylinder will discharge into the atmosphere and the spring react to restore the parts to normal position.

I claim:

In automatic train stopping apparatus, 65 the combination with the engineer's brake valve and throttle valve lever, of a substantially U-shaped yoke having the opposite limbs thereof slotted to receive the handle of said brake valve and said lever, means 70 for actuating said yoke to close the throttle valve and actuate the engineer's brake valve to apply the brakes, and means for guiding said yoke in its movement.

In testimony whereof I affix my signature 75 in presence of two witnesses.

WILLIAM W. JONES.
